UNITED STATES PATENT OFFICE.

EDWARD A. BYRNE AND JAMES P. LENAHAN, OF CINCINNATI, OHIO.

BEER-FAUCET.

SPECIFICATION forming part of Letters Patent No. 325,316, dated September 1, 1885.

Application filed June 18, 1884. (No model.)

To all whom it may concern:

Be it known that we, EDWARD A. BYRNE and JAMES P. LENAHAN, citizens of the United States, residing at Cincinnati, in the county of Hamilton and State of Ohio, have invented certain new and useful Improvements in Beer-Faucets, of which the following is a specification, reference being had therein to the accompanying drawings.

Our invention comprises a novel construction of those faucets having air-inlets, and which are employed more especially for drawing off beer, ale, and other liquors from kegs and similar receptacles. Heretofore it has been customary to pass the air tube or inlet through the heel of the faucet and carry the upper end of said tube almost to the top of the keg, so as to allow the air to act directly on the surface of the liquor, and thereby afford the proper vantage the instant the faucet is opened. Practical experience, however, has demonstrated that this is a very defective arrangement, inasmuch as the introduction of the air within the keg causes the beer or other liquor to become sour unless it is drawn off quite rapidly; hence such faucets are not adapted for use in small saloons, the proprietors of which places of resort demand a faucet that will afford the necessary vantage, and yet will not cause their liquors to become flat and unsalable. To meet these requirements we have devised a faucet the heel of which has one or more lateral ports, while the inner end of said heel is closed, so as to prevent the liquor taking a direct central passage through the axial channel. Furthermore, the discharging end of the tube or inlet is located in the rear of these ports in order that the flow of beer through the latter will cause a current of air to traverse said inlet and mingle with the liquor as it escapes from the faucet. By this arrangement the proper vantage is afforded, while at the same time there is no possibility of the air entering the keg or barrel, it being understood that the construction of the device is such as to allow the inlet to be opened only when the faucet-plug is so turned as to draw off the liquor, as hereinafter more fully described.

In the annexed drawings, Figure 1 is an axial section showing our improved faucet applied to a beer-keg, the plug of said faucet be-

ing opened to allow free flow of the liquor. Figs. 2 and 3 are enlarged axial sections of two modified forms of the faucet-heel. Fig. 4 is a transverse section of the heel seen in Fig. 3, said section being taken at the line 6 6. Fig. 5 is an axial section of a device that may be employed for regulating the flow of air into the inlet-tube of the faucet.

The faucet-barrel A, which may be of any suitable size and material, is provided with the customary channel or axial bore, B, and discharge-nozzle C, near which latter is located the plug D, having a port, E, that communicates with channel B when said plug is properly turned. Furthermore, this plug has a secondary port, F, that affords a channel leading from an opening, G, of the barrel to the front end of an inlet tube or pipe, H, whose discharging end is located within the heel I of the faucet. The extreme rear end of this heel is closed, so as to prevent the liquor flowing directly into the channel B; but one or more lateral ports, J, are made through this heel into said channel or bore. These ports are located at some distance in front of the closed end of the heel, and the discharging extremity of the pipe or tube H terminates in the rear of said ports.

K is a solder or other air-tight joint made at the place where the pipe H enters the faucet-heel.

L is the head of a barrel or keg or other vessel for containing liquors on tap.

When the heel I is properly inserted in the head L, and plug D turned around at right angles to the position seen in Fig. 1, it is evident beer cannot escape from the faucet. Neither can air enter through it; but the instant said plug is turned so as to bring its port E in line with channel B the beer flows freely through the faucet and is discharged at nozzle C. Now, this turning of plug D brings its secondary port F in line with opening G and pipe H, thereby allowing air to traverse said pipe and be discharged near the closed end of heel I.

As the beer flows at a high velocity through the lateral ports J into the channel B, and as said ports are situated in front of the discharging end of pipe H, it is evident the advancing current of liquor drags the air from said pipe along toward the nozzle C. Consequently there is no possibility of air escaping through the

ports J and ascending within the keg, because it is not sufficiently powerful to oppose the liquor flowing through said ports. Although the air does not enter the keg, yet the discharge of beer from the faucet is as free and perfect as though the air were admitted above the liquor. In fact the discharge is in some cases so rapid as to necessitate the application to the tube H of a cock, N, or its equivalent controlling device. When a keg is first tapped, this cock is to be partially closed, so as to admit a limited supply of air into the faucet; but as the liquor is drawn off said cock is to be gradually opened for the purpose of affording a more free ventage. The cock, however, may be dispensed with, and the opening G may be threaded internally to receive a screw plug, O. (Seen in Fig. 5.) This plug has a longitudinal groove or channel, P, that increases both in width and depth as it approaches the point of said plug, in order that the supply of air to the secondary port F may be increased in proportion as said plug is advanced, while its complete retraction will effectually exclude air.

In the modification of the invention seen in Fig. 2 the discharging end of the air-tube H is shown bent upwardly, while a downward bend of the same is indicated by dotted lines; but in Fig. 3 a channel, H', is cast in the upper side of the faucet, which channel takes the place of the external pipe or tube, H. This channel opens into a chamber, R, at the rear end of the faucet-heel, a perforated head, S, serving to divide said chamber from the axial bore B. T is a cap that may be either soldered or screwed onto the heel, so as to cover the chamber R. Furthermore, in this illustration the port J takes the shape of a longitudinal slot made in the lower side of the faucet, thereby enabling the keg to be completely emptied before air can enter it. This modified form of faucet operates in precisely the same manner as does the device seen in Fig. 1, the discharge of beer through the port J causing air to traverse the perforation or perforations of head S, and thereby afford the desired ven-

tage. Finally, an inclined barrier (indicated by the dotted lines U in Fig. 3) may project upwardly from the rear end of slot J, so as to deflect the current of air toward the top of the faucet, and thereby render it still more difficult for said current to flow back into the beer contained in the keg.

We claim as our invention—

1. A faucet having one or more inlet-ports communicating with its main or discharge channel, and a device for admitting air into said channel in the rear of said ports when the plug is opened, substantially as herein described.

2. A faucet having one or more inlet-ports communicating with its main or discharge channel, a device for admitting air into said channel in the rear of said ports when the plug is opened, and an independent appliance for controlling the flow of air through said device, substantially as described.

3. A faucet having an inlet-port on its lower side communicating with the main or discharge channel and a device for admitting air into said channel in the rear of said port when the plug is opened, substantially as herein described.

4. The combination of faucet A B C I, channeled plug D E F, opening G, and air-duct H, whose discharging end is located in the rear of inlet port or ports J, as and for the purpose specified.

5. The combination of faucet A B C I, channeled plug D E F, opening G, and duct H, the latter being provided with an independent appliance for regulating the entrance of air and having its discharging end located in the rear of inlet port or ports J, as and for the purpose specified.

In testimony whereof we affix our signatures in presence of two witnesses.

EDWARD A. BYRNE.
JAMES P. LENAHAN.
